UNITED STATES PATENT OFFICE.

GEORGE H. VAN ARNAM, OF FORT WAYNE, INDIANA, ASSIGNOR TO VAN ARNAM MANUFACTURING COMPANY, A CORPORATION OF INDIANA.

TOILET-SEAT ATTACHMENT.

Application filed August 8, 1924. Serial No. 730,797.

To all whom it may concern:

Be it known that I, GEORGE H. VAN ARNAM, a citizen of the United States of America, and resident of Fort Wayne, in the 5 county of Allen and State of Indiana, have invented certain new and useful Improvements in Toilet-Seat Attachments, of which the following is a specification.

This invention relates to improvements in 10 toilet seat attachments in which a seat for an infant is provided for use in conjunction with the usual toilet seat for an adult, and the object thereof is to provide automatic centering means on the infant seat for alining it in position on adult seats which vary 15 in respect to the sizes of their openings. Another object is to so construct the supporting and securing means of the attachment so that it may be applied to the adult 20 seat without marring the finish thereof.

These objects are accomplished by the construction illustrated in the accompanying drawings, in which:—

Fig. 1 is a bottom plan view of a structure 25 embodying the invention; and

Fig. 2 is an elevation in central section showing the invention applied to an ordinary adult toilet seat.

The characters appearing in the description 30 refer to parts shown in the drawings and designated thereon by corresponding characters.

The invention comprises a rectangular seat 1, preferably of wood, having an opening 2 therein, the seat being proportioned 35 so that when placed upon a regular toilet seat 3 it will cover the opening 4 therein.

To the bottom of the seat 1, adjacent the rear end 5 thereof is secured a spring wire 40 frame 6 by means of staples 7 that are driven astride of the wire forming the frame into the wooden seat, there being a metallic plate 8 interposed between the frame and the bottom of the seat at the instance of each staple, 45 and through which the corresponding staple is driven. The frame is shaped with a pendant loop 9, the lower extremity 10 of which is turned backwardly in a horizontal plane. The frame has laterally disposed 50 arms 11, the extreme ends being turned upwardly, which ends extend up into the wooden seat 1, the seat being drilled at corresponding points for the reception of said ends. The sides 13 of the frame that 55 intervene between the corresponding arms

11 and the pendant loop 9 are curved to conform to a radius, the axis of which centers at the instance of the upturned end of the corresponding arms. The curved sides of the frame pass loosely through 60 the corresponding staples and have sliding bearing on the plates 8, which plates serve to hold the frame from rubbing against the wooden seat when the sides of the frame are moved forwardly and backwardly in the staples. The frame is formed 65 of spring wire and initially bent so that the looped middle part thereof including the pendant loop tends to assume and retain its rearwardmost position. 70

Adjacent the forward end 14 of the seat 1, at the bottom thereof, is a pendant rubber covered wire loop 15 having lateral arms 16 each of which is rigidly secured to the seat by corresponding staples 17, the outer end 18 of each arm being turned upwardly and extended into the wooden seat so that the loop is held fixedly in place. Also, the bottom of the seat 1 has fixed thereon adjacent each of its corners a cushion 20 of rubber 75 or felt, which cushions have bearing on the top of the seat 3 when the attachment is positioned thereon, and serve to prevent the seat 1 and the wire frame from injuring the seat 3 by contact directly with the top 80 thereof. 85

In utilizing the invention the attachment is applied to the seat 3 in a forward position to admit of the introduction of the pendant loop 9 through the opening 4 of the adult 90 seat, and subsequently moving the seat 1 rearwardly in order to extend the extremity 10 of the loop beneath the adult seat. The loop bears against the rear portion of the seat 3 in the opening thereof with the resistance of the frame as the seat 1 is pressed rearwardly. The front end of the seat 1 is lowered onto the adult seat as it is moved rearwardly sufficient as to admit of the passage of the fixed loop 15 into the opening 4 of the adult seat at the front end thereof, said fixed loop serving as a stop to prevent relative forward movement of the attachment on the adult seat. As the frame bears 95 against the adult seat at the rear of its opening, its spring tendency to move the seat forwardly is resisted by the engagement of the stop against the seat at the opposite end of its opening, so that the attachment is sustained in alined position on 100 105 110

the adult seat with corresponding stress while it is in use. The attachment is readily removed by first elevating its front end to withdraw the stop from the opening in the adult seat, and subsequently moving the attachment forwardly so as to withdraw the pendant loop from the opening.

What I claim is:

1. A child's seat attachment for a regular 10 toilet seat, comprising an apertured supplemental seat applicable to be superimposed upon the regular seat, a spring wire frame disposed on the bottom of the supplemental seat at the rear portion thereof, said frame 15 having a central pendant loop with a rearwardly extending lower extremity, and having lateral swinging arms, each of which has an upturned end extending into said supplemental seat and upon which the arm 20 turns pivotally, said frame also having curved sides between the corresponding arms and the pendant loop, the radius of each side being centered at the instance of the upturned end of the corresponding arm; a 25 chafing plate interposed between each of said curved sides of the frame and the supplemental seat; a staple loosely securing each of said curved sides to the seat and extending through the corresponding plate; 30 and a pendant stop projecting from the bottom of the supplemental seat adjacent the front end thereof.

2. A child's seat attachment for a regular

toilet seat comprising an apertured supplemental toilet seat applicable to be positioned on the regular seat, a spring wire frame having radially disposed arms pivotally movable on the supplemental seat beneath the rear portion thereof, said frame also having a central pendant loop with a rearwardly extending lower extremity, said loop being movable accordingly as the arms are actuated; means limiting the movement of the frame and loosely securing it to the supplemental seat; and a pendant stop projecting from the bottom of the supplemental seat adjacent the front end thereof.

3. A child's seat attachment for a regular 50 toilet seat, comprising an apertured supplemental seat; a frame in connection with the supplemental seat beneath one end thereof, and having a pendant hook that has spring restrained movement relative thereto; and a pendant stop projecting from the bottom of the supplemental seat adjacent the 55 end thereof opposite said loop, said loop and stop being applicable through the opening of the regular seat to hold the supplemental seat alined thereon.

In testimony whereof I affix my signature 60 in presence of two witnesses.

GEORGE H. VAN ARNAM.

Witnesses:

GERTRUDE A. MULLER,
HAZEL CALVIN.
